UNITED STATES PATENT OFFICE.

LEON CAMMEN, OF TUCKAHOE, NEW YORK.

CENTRIFUGAL CASTING MACHINE.

Application filed March 30, 1922. Serial No. 548,195.

To all whom it may concern:

Be it known that I, LEON CAMMEN, a citizen of the United States, and resident of the village of Tuckahoe, Westchester County, 5 State of New York, have invented certain useful Improvements in Centrifugal Casting Machines, of which the following is a specification.

The present invention refers to a new construction of centrifugal casting machines, in which means are provided for rapid insertion and removal of molds, and for supporting the mold in such a manner as to make it find its own center position with respect to the axis of rotation, and to reduce the bursting stresses thereon. The latter is of particular importance where a hot mold is used, as the high temperature of the mold reduces appreciably the tensile strength of 20 the metal thereof. It is also of importance where a split mold is used, and where it is desired to use the mold supports as an additional means to keep the parts of the mold together as against the action of the bursting stresses.

In the illustrations,

Fig. 1 shows a longitudinal section of the barrel of the spinning machine;

Fig. 2 shows a section of the barrel normal to the longitudinal axis;

Fig. 3 shows the tapered bed, or external dovetail, for the sliding gibbs;

Fig. 4 shows a tapered gib;

Figs. 5 and 6 show section of the barrel 35 similar to those of Fig. 2 but in modified construction, being variants of that in Fig. 2.

The essential features of the present invention refer particularly to the barrel part 40 of the centrifugal casting machine. In this case the barrel consists essentially of the shell, usually steel, 4 provided with taper dovetail slots, such as are shown in 39 and 40, Fig. 3, and tapered gibbs or keys 3, sliding in the tapered dovetails. The dovetails and gibbs have the same degree of taper, but it is important to note that whereas the dovetail has its taper at the bottom, the gib is tapered in its top surface, as shown, respectively, in Figs. 3 and 4, so that the slot in the dovetail is of the same depth throughout. This is important, as otherwise the gibbs will not work. As the gibbs of which there may be any number from two up, are all bound to 55 some terminal element, as by straps 8 to

ring 7, they can slide in their beds for equal distances only, and therefore, if the taper of all the gibbs is the same, they are bound to remain symmetrical to each other, which means that if initially they have been set so that their faces are tangent to some circle or cylinder all these faces will remain tangent to a circle no matter what the displacement of the gibbs may be, though the diameter of the cylinder or circle or tangency will vary 60 with the position of the gibbs.

The operation of the centrifugal casting machine is as follows. To insert the mold, the head 20 is opened by shifting the locking screw 19 into the position indicated by the broken line at 18, and by swinging the head 20 on the hinge 13. A pull is then exerted on a ring (not shown) to which all the gibbs are attached, and this causes the gibbs to move in unison outwards, i. e., towards the head 70 end. As the gibbs move outward in the beds, they spread out, and this permits to insert the mold 1 between them. The mold goes as far as the abutment 7 at the end of the barrel, all the gibbs being attached to the 75 abutment 7 by some means, as by straps 8. The pressure of the mold sends the abutment back towards the tail end of the mold; the gibbs are carried backwards with it, and as they do, they contract until they come to 80 grip the mold. The pressure which the gibbs exert on the mold depends entirely upon how hard the mold is pressed in.

Furthermore, as the gibbs move always in such a manner that their faces are tangent to 85 some cylinder, it is obvious that if the mold is also cylindrical or if its surface is symmetrical with respect to its longitudinal axis, the mold, through the very fact of its being held by the gibbs, will find its own 90 center. As any mechanic can see, however, it is possible to produce such a combination of mold and gibbs as to give the axis of the mold any desired position with respect to the axis of the barrel.

When the mold is cylindrical in its outside surface, the gibbs construction shown in Fig. 2 is preferable. At times, however it is desirable to give the mold an external surface shaped otherwise than as a cylinder. 105 This is the case, e. g., when the mold is split longitudinally, and its parts are held together by external lugs 22 and 23, and an external dovetail 24 embracing the lugs, as in Fig. 6. The presence of such lugs on the 110

outside surface of the mold would make machining to a cylinder rather expensive, and therefore the mold is provided with a number, two, four, six or more, of flat surfaces 28. While not absolutely necessary, it is desirable for the sake of insuring a better dynamic balance, to have these flat surfaces machined in such a manner that they would be tangent to a circle described with a center 10 located on the longitudinal axis of the mold, and that the surfaces be disposed symmetrically with respect to the longitudinal axis, which means that the angles formed by the radii of the circle of tangency passing 15 through the middle of the projection of the plane 28 in Fig. 6 of each adjoining pair of surfaces be the same. Of course, it is not absolutely necessary to make the faces 28 flat, but this is the cheapest and easiest surface 20 to make, and nothing is gained by adopting a curved surface for 28. The face of the gibs has to be made to correspond to that of 28, as shown in Fig. 6; otherwise, the construction and method of operation of the gibs 25 remains unchanged. The construction shown in Fig. 6 has the advantage that it offers a very powerful support to the mold, about 40 per cent of mold surface being directly supported by the gibs. On the other hand, however, it affords better opportunity 30 for the escape of heat from the mold, which may be desirable in some cases, and objectionable under other conditions, as any man skilled in this art may see.

35 A further modification of the same construction is shown in Fig. 5. There the barrel itself is also split, and held together as by bolt 32, the two parts of the mold being dovetailed into the gibs pieces (not shown) as at 29. The operation is the same as in the other cases, but the mold may be opened by opening the barrel so that it is not necessary to pull the mold out every time a casting is made.

45 After the mold has been inserted into the barrel, it is necessary to exert a pressure on it to close it effectively by forcing the gibs around it. This may be done by applying force to the mold or gibs; one way of doing it is shown in Fig. 1 where pressure may be applied by screw 15 and wheel 16 through press block 14. The construction is merely a screw press made part of the casting machine.

55 The barrel is supported in the usual manner on some kind of rollers, not shown here, acting on bearings as 10 and 11.

The advantage of the construction described above, as compared with the usual 60 method of supporting molds in casting machines by bearings located at various intervals, lies in the fact that the mold is supported all along its length, and this reduces the tendency of the mold to bend, a matter of great importance in view of the high speeds of ro-

tation of molds in centrifugal casting, great strains thereon, and, in the hot mold process, reduced stiffness of the metal of the mold.

The beds or dovetails for the sliding of the keys or gibs may be cut directly in the shell 4 of the barrel, as indicated in Fig. 1. This is however an inconvenient process, especially in long molds, as anyone who had experience in machine work can easily realize. There is a simpler way however, and that is to cut the dovetail slots in separate pieces, and then attach them, as by screws, bolts, rivets or otherwise to the shell 4. To do this, one may start with a flat piece of metal of proper length. The slot shown in the upper part of 39 and 40 may be cut first, as it is of equal depth throughout. The piece is then reversed, placed, say, on a tapered fixture in a planer, and machined to the proper taper as indicated by a comparison of thickness between 39 and 40. It may be then finished with a proper tool that will give it the curvature shown at the bottom of the piece, this being of the same radius as the inside wall of the shell 4, to bring the insert piece into closer contact with the shell.

The face pieces 2, Fig. 2, may be made in one piece with the keys 3, or separately, in which case they may be connected by screws as at 5. It may be of advantage to use for the face pieces 2 a metal of a higher melting point or softening temperature than for the keys 3, or to protect the face piece 2 by a layer of refractory material from the heat of the mold with which it comes into contact.

Wherever reference is made to the taper of the slot in this specification, it should be clearly understood that this refers to the angle between the axis of the mold and the plane of the bottom of the slot or the plane of the top of the slot, but not as the angle between the plane of the bottom of the slot and the plane of its top; in other words, the depth of the slot is assumed to be uniform throughout, this being the only condition under which the key can move in the slot.

In reference to the key or gib, it should be understood that the two terms are essentially interchangeable, and that the bottom of the key is of the same width throughout; by taper of the gib is meant the angle formed by its bottom plane, such as 38, with its top plane opposite thereto.

Where the slot is cut not in the shell directly, but in a separate body attached to the shell, which latter is cylindrical on the inside, the taper of the slotted part may be defined as the angle between the plane of the top or the plane of the bottom of the slot on one hand, and a generating line of the shell, preferably one intersected by a

radius of a section of the shell where such radius intersects the slot in two equal parts.

I claim:

1. A machine for centrifugal casting comprising a shell, tapered slots disposed longitudinally in said shell, and tapered keys sliding in said tapered slots. 5
2. A machine for centrifugal casting comprising a shell, tapered slots disposed longitudinally in said shell, tapered keys sliding in said slots, and means for moving said keys in said slots. 10
3. A machine for centrifugal casting comprising a shell, tapered slots disposed longitudinally in said shell, tapered keys sliding in said tapered slots, and means for moving said keys in said slots so that said keys all travel through the same distances in the same time, and move all in the same 15 direction. 20
4. A machine for centrifugal casting comprising a shell, tapered slots disposed longitudinally in said shell, tapered keys sliding in said tapered slots, said keys having their faces tangent to a cylinder, and means for moving said keys in said slots simultaneously, which means, so that their faces all remain tangent to a cylinder, the diameter of said cylinder of tangency varying with the distance through, and direction in, which the keys have moved. 25
5. A machine for centrifugal casting comprising a shell, metal bodies attached to said shell on the inside, tapered slots in said bodies disposed in a direction parallel to the longitudinal axis of said shell, and tapered keys sliding in said tapered slots. 30
6. A machine for centrifugal casting comprising a shell, metal bodies attached to said shell on the inside, tapered slots in said bodies disposed in a direction parallel to the longitudinal axis of said shell, tapered keys sliding in said tapered slots, and means for moving said keys in said slots. 35
7. A machine for centrifugal casting comprising a shell, tapered slots disposed longitudinally in said shell, tapered keys sliding in said tapered slots to receive the mold, and means for moving said keys and for causing them to grip the mold by the mold itself. 40
8. A machine for centrifugal casting comprising a shell, metal bodies attached to said shell on the inside, tapered slots in said bodies disposed in a direction parallel to the longitudinal axis of the shell, tapered keys 45
9. A machine for centrifugal casting comprising a shell, metal bodies attached to said shell on the inside, tapered slots in said bodies disposed in a direction parallel to the longitudinal axis of said shell, tapered keys sliding in said tapered slots and means for moving said keys in said slots so that said keys all travel through the same distance in the same time, and move all in the same direction. 60
10. A machine for centrifugal casting comprising a shell, metal bodies attached to said shell on the inside, tapered slots in said bodies disposed in a direction parallel to the longitudinal axis of said shell, tapered keys sliding in said tapered slots, said keys having their faces tangent to a cylinder, and means for moving said keys in said slots simultaneously, which means, so that their faces all remain tangent to a cylinder, the diameter of said cylinder of tangency varying with the distance through, and direction in, which the keys have moved. 65
11. A machine for centrifugal casting comprising a shell, tapered slots disposed longitudinally in said shell, and tapered keys sliding in said tapered slot to receive the mold, the face of each key being finished so as to fit the part of the mold with which the key comes in contact. 70
12. A machine for centrifugal casting comprising a shell, metal bodies attached to said shell on the inside, tapered slots disposed in said bodies in a direction parallel to the longitudinal axis of said shell, and tapered keys sliding in said tapered slots to receive the mold, the face of each key being finished so as to fit the part of the mold with which the key comes in contact. 75
13. A machine for centrifugal casting comprising a shell, tapered slots disposed longitudinally in said shell, tapered keys sliding in said tapered slots, a head to close said shell at one end, and a screw passing through said head to move the keys. 80

Signed in New York, in the county and State of New York, March 28, 1922. 85
